UNITED STATES PATENT OFFICE

2,657,851

COLLAPSIBLE BOX

Henry L. Metzger, Castleton-on-Hudson, N. Y.,
assignor to Fort Orange Paper Company, Cas-
tleton-on-Hudson, N. Y., a corporation of New
York

Application December 9, 1949, Serial No. 132,172

1 Claim. (Cl. 229—38)

1 This invention relates to an improved collapsible type of box, and, more particularly, to such a box which has an improved automatic type bottom therein.

Generally, it is an object of the invention to provide such a box which is simple and economical to manufacture by providing a single blank of cut and scored paperboard material which is easily folded and secured together in collapsed position for shipping purposes, and which readily can be erected into squared position ready for use, the box having an automatic type bottom therein which is positive in action and adapted to eliminate fingering or manipulation thereof on the part of the user to complete the opening of the bottom.

More specifically, it is an object of the invention to provide such a box having a bottom wall hingedly connected to the bottom edge of a front wall along a line of fold, the bottom wall having a cut-out section extending inwardly from its free end to a zone which is at least half the distance from its free end to the line of fold to provide a glue flap constituting a portion of the bottom wall and foldable against the bottom of a remaining portion thereof, the bottom wall being secured to the side walls, and a rear wall being secured to one of the side walls, whereby the bottom wall is adapted automatically to unfold to opened, bottom-forming position from a folded and collapsed position when the walls of the box are squared with respect to each other from collapsed position.

Another object of the invention is to provide such an automatic bottom for a box in which a glue flap constitutes a portion of the bottom wall and is smaller in area than the remaining portion of the bottom wall.

A further object of the invention is to provide such an automatic bottom in which the bottom wall has a single fold line, defining a glue flap constituting the remaining portion of the bottom wall, extending from one end of the fold line to which the bottom wall is attached to the bottom edge of the front wall, diagonally to the depth of the cut-out section provided in the bottom wall.

A further object of the invention is the provision of such a bottom wall having a single diagonal fold line as above described which forms an angle of approximately 45° with the fold line along the bottom of the front wall to which the bottom wall is attached.

Other objects of the invention will in part be obvious and will in part appear hereinafter.

The invention accordingly comprises an article of manufacture possessing the features, properties, and the relation of elements which will be exemplified in the article hereinafter described

2 and the scope of the application of which will be indicated in the claim.

For a fuller understanding of the nature and objects of the invention, reference should be had to the following detailed description, taken in connection with the accompanying drawings, in which:

Fig. 1 illustrates a die-cut and scored blank of paperboard material for providing a preferred form of collapsible box with an automatic type bottom embodying the invention;

Fig. 2 shows the blank of Fig. 1 partly folded and glued together;

Fig. 3 shows a further step in the operation of folding the blank of Fig. 2 for securing it together in collapsed position;

Fig. 4 shows the blank of Fig. 3 completely folded and secured together ready for shipping and erection by the user;

Fig. 5 is a perspective view illustrating the manner in which the collapsed box of Fig. 4 is manipulated to square the same and position the automatic type bottom;

Fig. 6 is a view somewhat similar to Fig. 5 with a portion thereof broken away showing the automatic bottom in position upon squaring of the box; and

Fig. 7 is a somewhat smaller perspective view showing the completely erected box ready for filling.

Referring more particularly to Fig. 1, there is indicated a cut and scored blank of paperboard material having side walls which conveniently may be referred to as a front wall 10, side walls 11 and 12 and a rear wall 13 defined by vertical score lines 14, 15 and 16, respectively, and horizontal score lines 17, 18, 19, 20, 21 and 22, respectively.

Extending from the bottom edge of the front wall 10, along the fold line 21 is a bottom wall indicated generally at 23 which provides the automatic bottom for the collapsible box. This wall has a cut-out section C which extends inwardly from its free end to a zone which is at least half the distance from its free end to the score line, or line of fold 21, along the bottom edge of the front panel 10. The cut-out bottom wall 23 has but a single line of fold indicated by a score line 24 which extends diagonally from one corner of the front wall 10, beginning at the score line 21, at an angle of 45° and terminating at the depth of the cut-out section C. The score line 24 defines a glue flap 25 which constitutes a portion of the bottom wall leaving the remaining portion thereof forming a right triangle 26 which has no other score or fold lines therethrough. The leg of the triangular portion of the bottom

wall 26 is defined by a score line 27. The base of the triangular portion of the bottom wall falls along the score line 21, and the score or fold line 24 falls along the hypotenuse of the triangle as indicated.

An extension panel 28 is hingedly attached to the bottom wall along the score line 27 opposite the glue flap 25 and this panel terminates at one end adjacent the side wall 12, the panel having a foldable corner portion 29 as defined by a score line 30.

Another extension panel 31 is hingedly attached to the bottom of the other side wall 11 and has a corner portion cut therefrom as indicated at 32. The side walls 11 and 12 have infolding top corner flaps 33 and 34, extending from their top edges along the score lines 17 and 18 respectively.

The rear wall has a cover 35 extending therefrom as defined by the score line 19. A score line 36 through the cover 35 defines a tuck-in flap 37. Extending from the bottom of the rear wall is a false bottom flap or panel 38 defined by the score line 22. Extending from the side edge of the rear wall 13 is a glue flap 39 as defined by the score line 40.

In the operation of folding and securing the blank shown in Fig. 1 into collapsible carton formation, the corner portion 29 is folded around the score line 30 upon the extension panel 28 and any suitable glue or adhesive is applied to the exposed surface of the corner portion 29, or to a coinciding area on the side panel 12. The bottom panel is then folded along the score line 21 onto the front panel 20 so that the corner portion 29 becomes adhesively affixed to the side panel 12. The glue flap 25 is then folded around panel 12. The glue flap 25 is then folded around the score line 24 and upon the remaining portion of the bottom wall 26 as shown in Fig. 2. An adhesive is then applied to the exposed surface of the glue flap 25, or to a coinciding area on the extension panel 31. In the meantime, the false bottom 38 is folded upon the rear wall 13 and the latter, together with the false bottom, is then folded over upon the side panel 12 as shown in Fig. 3. An adhesive is applied to the exposed surface of the glue flap 39, whereupon the side wall 11 is folded over onto the front wall 10 so that the extension panel 31 becomes adhesively secured to the glue flap 25 and the marginal edge of the side wall 11 becomes adhesively secured to the glue flap 39, the cut edge 32 coinciding with a similarly cut edge 41 on the glue flap 39. The cut and scored blank, when folded and adhesively secured together as above described, has the appearance of the collapsible carton shown in Fig. 4 and is ready for shipment to the user in bulk quantities.

When the user receives the collapsible carton, it is but necessary to squeeze opposite diagonal ends or corners in the manner shown in Fig. 5 in order to square the side walls, and the automatic bottom 23 will unfold to opened, bottom-forming position from a folded and collapsed position as illustrated in Fig. 6 of the drawings. The false bottom 38 will then fall into a position overlying the automatic bottom 23 and cover the cut-away section C therein, and the box will take on the appearance illustrated in Fig. 7 ready to be filled with any suitable commodity, after which the flaps 33 and 34 are infolded and the cover 35 pushed down thereon, the tuck-in flap 37 being inserted between the ends of the flaps 33 and 34 and the adjacent front wall 10.

It will be understood that the invention as de-

fined by the claims embodies such boxes which are rectangular in cross-section as well as those which are square in cross-section as herein illustrated. In either case, the score line 24 should form an angle of approximately 45° with the score line 21 and extend to the depth of the cut-out section C. The cut-out section C might be of a different configuration depending on the cross-sectional shape of the box and is not necessarily confined to the configuration shown in the drawings.

It will thus be seen that the objects hereinbefore set forth may readily and efficiently be attained and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention which, as a matter of language, might be said to fall therebetween.

Having described my invention, what I claim as new and desire to secure by Letters Patent is:

In a cut and scored blank of paperboard material adapted to be folded and secured together to provide a collapsible box comprising front, rear and side walls, a bottom wall hingedly connected to the bottom of said front wall only along a fold line, said bottom wall having a cut-out section with a cut edge extending inwardly from one corner of its free end to a zone which is at least half the distance from said free end to said fold line and lying in a plane which constitutes a diagonal fold line that bisects the angle of the opposite corner to provide a glue flap constituting a portion of said bottom wall and foldable against the bottom of the remaining portion thereof and within the confines of said bottom which diagonal fold line extends from one end of said first named fold line, beginning at said opposite corner, to the depth of said cut-out section, said glue flap being smaller in area than said remaining portion of said bottom wall, which portion forms a right triangle, an extension panel hingedly integral with said open bottom wall only along one side thereof opposite said glue flap and terminating at one end adjacent a side wall, foldable upon itself, and in said foldable position being adapted adhesively to be secured to an adjacent side wall, an extension panel hingedly attached to the bottom of the other side wall and adapted adhesively to be secured to the glue flap constituting a portion of said bottom wall, and means adapted adhesively to secure said rear wall to said last named side wall; whereby said bottom wall is adapted automatically to unfold to opened, bottom-forming position from a folded and collapsed position when the walls of the box are squared with respect to each other from collapsed position.

HENRY L. METZGER.
